UNITED STATES PATENT OFFICE

103,938

DESIGN FOR A TEXTILE FABRIC OR SIMILAR ARTICLE

Adolph C. Jaeger, Port Chester, N. Y.

Application February 19, 1937, Serial No. 67,740

Term of patent 7 years

To all whom it may concern:

Be it known that I, Adolph C. Jaeger, a citizen of the United States, residing at Port Chester, county of Westchester, State of New York, have invented a new, original, and ornamental Design for a Textile Fabric or Similar Article, of which the following is a specification, reference being had to the accompanying drawing, which forms a part thereof, and in which I have shown a unit of the design.

The figure of the drawing is a plan view of the fabric showing my design in which the design unit is disclosed, the same consisting of groups of figures repeated in both directions.

I claim:

The ornamental design for a textile fabric or similar article substantially as shown and described.

ADOLPH C. JAEGER.
